UNITED STATES PATENT OFFICE

2,062,659

MINING APPARATUS

Charles F. Osgood, Claremont, N. H., assignor to
Sullivan Machinery Company, a corporation of
Massachusetts

Application November 20, 1933, Serial No. 698,797

49 Claims. (Cl. 262—28)

This invention relates to mining apparatus, and more particularly to improvements in coal mining apparatus of the combined horizontal and shear cutter, track supported and guided type.

5 An object of this invention is to provide an improved coal mining apparatus. Another object is to provide an improved coal mining apparatus of the combined horizontal and shear cutter type. A further object is to provide an improved coal mining apparatus of the combined horizontal and shear cutter, track supported and guided type, adapted to effect its cutting functions while supported by a mine track-way. A still further object is to provide an improved adjustable supporting structure for the kerf cutting mechanism of such an apparatus. Yet another object is to provide an improved adjustable supporting structure for the kerf cutting mechanism whereby the kerf cutter may be positioned to cut kerfs in the coal face in any desired horizontal plane between the mine roof and mine floor and to cut vertical kerfs at any location between the ribs of the entry. A further object is to provide, in such an apparatus, improved adjustable kerf cutting mechanism operative to cut kerfs in the coal face in parallel planes either horizontally or vertically and in intersecting planes. Yet another object is to provide an improved adjustable kerf cutting mechanism whereby kerfs may be cut at or near the level of the mine floor outside and below the level of the mine trackway, in any desired horizontal plane between the mine roof and the mine floor and in vertical planes between the ribs of the entry. Another object is to provide an improved coal mining apparatus of a truly universal character having an extremely wide range of adjustment of the kerf cutting mechanism whereby kerfs may be cut in the mine wall at practically any desired location. These and other objects of the invention will, however, hereinafter more fully appear.

In the accompanying drawings there is shown, for purposes of illustration, one form which the invention may assume in practice.

In these drawings,—

Fig. 1 is a plan view of the illustrative embodiment of the improved mining apparatus.

Fig. 2 is a side elevational view of the mining apparatus shown in Fig. 1.

Fig. 3 is a horizontal sectional view taken substantially on line 3—3 of Fig. 2, with parts shown in plan.

Fig. 4 is a vertical sectional view taken substantially on line 4—4 of Fig. 3.

Fig. 5 is a transverse vertical sectional view taken on line 5—5 of Fig. 3.

Fig. 6 is a longitudinally extending vertical sectional view taken substantially on line 6—6 of Fig. 1.

Fig. 7 is a horizontal sectional view taken substantially on line 7—7 of Fig. 6.

Fig. 8 is a horizontal sectional view taken substantially on line 8—8 of Fig. 6.

Fig. 9 is a horizontal sectional view taken substantially on line 9—9 of Figs. 7 and 10.

Fig. 10 is a horizontal sectional view taken substantially on line 10—10 of Fig. 9.

In this illustrative embodiment of the invention, there is shown a coal mining apparatus of the combined horizontal and shear cutter, track supported and guided type, adapted to operate from a mine trackway, and generally comprising a self-propelled portable base, herein in the form of a truck frame 1 mounted on wheels 2 adapted to run along a mine trackway 3.

Supported on the truck frame 1 for rotative movement relative thereto about a vertical axis is a horizontal turntable 4 having mounted thereon a frame 5, which constitutes the main supporting frame for the kerf cutting mechanism.

Mounted on the forward end of the frame 5 and overhanging the truck frame is the improved adjustable supporting structure, generally designated 6, for the kerf cutting mechanism 7, this structure comprising a single rigid swingable arm 8, a tiltable support 9, a swingable support 10, and a rotatable cutter carrying head 11.

The arm 8 is swingable vertically relative to the truck frame about a transverse horizontal axis at 12, adjacent the forward edge of the turntable, while the support 9 is swingable vertically relative to the arm about a horizontal axis 13 parallel with the arm pivot axis 12.

The support 10 is mounted on the tiltable support 9 for swinging movement about a vertical axis 14 lying in a longitudinal vertical plane perpendicular to the pivotal axes 12 and 13, while the cutter carrying head 11 is rotatably mounted on the swingable support 10 about a longitudinal axis at right angles to the support pivot axis 14.

Pivots mounted on the cutter head for swinging movement relative thereto about an axis at right angles to the head rotation axis, is an elongated plane cutter bar 15 having mounted on its margin, for circulation therewith, a cutter bit carrying cutter chain 16.

Suitable motor operated devices are provided for rotating the turntable 4, for operating the adjustable supporting structure 6, for operating the cutting mechanism 7, and for driving the truck 55

55

wheels to propel the apparatus along the mine trackway both during cutting and during transport, as will hereinafter be described.

Referring to the turntable mounting structure 5 for the kerf cutting mechanism 1, it will be noted that secured to the truck frame above the truck wheel axes is an annular turntable receiving frame 17 on which the circular turntable frame 18 is rotatably mounted, the frame 18 having an 10 upstanding annular flange 19 and the frame 18 having a depending annular flange 20, the frame 18 supporting a bearing sleeve 21 with which the flange 20 cooperates. Also formed on the frame 17 is an inner annular flange 22 supporting a 15 bearing sleeve 23 with which an inner depending annular flange 24 rotatably engages. The mechanism for rotating the turntable 4 at a relatively low speed suitable for cutting and at a relatively high cutter positioning speed, herein comprises 20 a motor 25 mounted on the truck frame at the rear of the turntable structure and having its power shaft connected by a coupling 26 to a shaft 27 suitably journaled within a housing 28 mounted on the rearward portion of the truck 25 frame. Fixed to the shaft 27 is a worm 29 meshing with a worm wheel 30 keyed to a sleeve 31 rotatively mounted on a transverse operating shaft 32, likewise suitably journaled within the housing 28 and within an upstanding bearing 30 bracket 33 formed integral with the adjacent side of the truck frame. The sleeve 31 is adapted to drive, through a plural speed, frictionally controlled, planetary transmission mechanism generally designated 34, the shaft 32. This transmission mechanism comprises a rotatable casting 35 frictionally controlled by a brake band 36 regulated by a hand wheel 37. A sliding clutch element 38 controlled by a clutch shipper member 39 is employed for attaining a relatively high 40 and a relatively low speed, this clutch member being alternatively engageable with the high and low speed terminal members 40 and 41 respectively of the transmission mechanism. As the specific structure of this planetary transmission 45 mechanism is well known to those skilled in the mining art, further illustration and description thereof are considered unnecessary. Splined to the transverse shaft 32 is a jaw clutch member 42 having an operating lever 43, and this clutch 50 member is shiftable to connect a bevel gear 44 to the shaft 32. This bevel gear meshes with 55 and drives a bevel gear 45 fixed to a vertical shaft 46, and this shaft in turn has fixed thereto a chain sprocket 47 connected by an endless chain 48 to a sprocket 49 keyed to a vertical shaft 50. The shafts 46 and 50 are suitably journaled within the truck frame, and the shaft 50 has keyed thereto and drives a spur gear 51 meshing with a large spur gear 52, herein formed integral with 60 the depending flange 20 of the turntable 4 (see Fig. 4). It will thus be seen that when the bevel gear 44 is connected to the shaft 32 and the clutch member 39 is operated in an appropriate manner, the turntable 4 may be rotated at either 65 a relatively high or a relatively low speed under friction control of the brake band 36 of the planetary transmission 34. The motor 25 is herein preferably of the reversible electric type, and it is accordingly evident that the turntable may be 70 rotated in either of opposite directions at either a high speed or a low speed, depending upon the direction of motor rotation. When the turntable 4 is disconnected from its rotating mechanism, 75 it may be locked against rotation by means of a

sliding locking element 53 (see Fig. 1) guided in a bracket 54 secured to the turntable supporting frame and engageable with the teeth of the gear 52 formed on the rotatable turntable frame.

The motor 25 and the planetary transmission 5 mechanism 34 also constitute driving means for the truck wheels to propel the apparatus along the mine trackway at either a relatively high transport speed or at a relatively low cutting speed. This truck wheel driving mechanism 10 comprises a chain sprocket 55 journaled on the shaft 32 and connectible thereto by the jaw clutch member 42, and this sprocket is connected by an endless chain 56 to a chain sprocket 57 fixed to the rear truck wheel axle. The front 15 and rear truck wheel axles are connected in driving relation by a chain and sprocket connection 58. A truck wheel brake is provided and comprises a brake drum 59 keyed to the rear truck wheel axle and with which cooperates a usual 20 brake band 60 controllable through connections 61 operated by a brake lever 62. From the foregoing it is evident that the truck wheels may be driven at either a high or a low speed under the control of the planetary transmission mechanism 25 34, and through the drive of the reversible motor in either of opposite directions at either speed whenever the clutch member 42 is operated to connect the truck driving member 55 to the shaft 32, and the truck wheel driving speeds 30 35 may both be frictionally controlled by the brake band 36. When the clutch member 42 is in the position shown in Fig. 1, i. e. its neutral position, both the turntable rotation and the truck wheel drive are disconnected from the motor 25.

Now referring to the kerf cutting mechanism, and more particularly to the improved adjustable supporting structure therefor, it will be observed that housed in the turntable frame 5 is a horizontal motor 63, herein preferably of the reversible electric type having the forward end of its power shaft 64 operatively connected to the devices for operating and adjusting the kerf cutting mechanism. In the present construction there are formed integral with the forward portion of the turntable frame 5, parallel forwardly projecting vertical frame portions 65, 65, and journaled within these frame portions is a horizontal hinge shaft 66 extending transversely of the arm 8. The supporting arm 8 has formed on its rear extremity parallel vertical frame portions 67, 67 overlapping the frame portions 65, 65 and pivotally mounted on the hinge shaft 66. The outer extremity of the arm 8 has formed thereon parallel vertical frame portions 68, 68, 55 and supported within these frame portions is a transverse hinge shaft 69 arranged with its axis parallel with the hinge shaft 66. Pivotally mounted on the hinge shaft 69 and overlapping the frame portions 68, 68 (see Fig. 7) are parallel vertical frame portions 70, 70 formed on the tiltable support 9. As shown most clearly in Fig. 6, formed on the tiltable support 9 are parallel, vertically spaced frame portions 71, 71 having supported therein a vertical hinge shaft 65 72 on which there are rotatably mounted parallel frame portions 73, 73 overlapping the frame portions 71, 71 and formed on the swingable support 10 on which the cutter carrying head 11 is rotatably mounted. The arm 8, the tiltable 70 support 9, and the swingable support 10 are independently swingable about their respective pivotal axes, and the cutter head 11 is rotatable relative to the support 10 through improved devices which will now be described.

As shown in Figs. 3 and 4, connectible to the forward end of the motor power shaft 64, as by an operator-controllable multiple disc clutch 74, is a worm 75 meshing with worm wheels 76 and 77 and simultaneously driving the latter in the same direction. These worm wheels are fixed to parallel vertical shafts 78 and 79 respectively, suitably journaled within the turntable frame 5. Keyed to the upper ends of these shafts 10 are spur gears 81, 81, and these gears mesh respectively with spur gears 82, 82 fixed to parallel vertical shafts 83 and 84, the latter likewise being suitably journaled within the turntable frame 5. Keyed to the shafts 83 and 84 respectively are worms 85 and 86 meshing with worm gear teeth 87 formed on the parallel frame portions 67, 67 of the arm 8. It will thus be seen that when the worm 75 is connected to the motor power shaft by the disc clutch 74, the worms 85, 86 meshing 20 with the worm gear teeth 87 on the arm 8 may be driven to swing the arm either upwardly or downwardly, depending upon the direction of motor rotation. If desired, however, a suitable reversing mechanism may be provided in the 25 drive so that the arm 8 may be swung either upwardly or downwardly without reversal of the motor. Keyed to the forward end of the motor power shaft 64 is a bevel gear 90 meshing with a bevel gear 91 journaled on the hinge 30 shaft 66 and in turn meshing with a bevel gear 92 fixed to the rear end of a shaft 93 suitably journaled within and extending longitudinally of the arm 8 (see also Figs. 6 and 7). Fixed to the forward end of the shaft 93 is a bevel gear 94 meshing with a bevel gear 95 journaled on the hinge shaft 69. The devices for tilting the support 9 about the axis 13 relative to the arm 8 herein comprise a hollow shaft 96 journaled on the hinge shaft 69 and driven by the bevel 35 gear 95. Fixed to the shaft 96 is a spur gear 97 meshing with an intermediate gear 98 journaled on a shaft 99 suitably supported within the parallel frame portions 68, 68. The gear 98 in turn meshes with a spur gear 100, likewise journaled 40 within the frame portions 68, 68. The gear 100 is journaled on a transverse shaft 101, in turn suitably journaled within the arm 8 (see also Fig. 8) and is connectible to this shaft to drive the latter by an operator-controllable clutch 102. 45 Fixed to the opposite ends of the shaft 101 are worms 103, 103 meshing with worm wheels 104, 104. These worm wheels are fixed to vertical shafts 105, 105 suitably journaled within the arm 8 and having fixed thereto worms 106, 106 meshing 50 with worm gear teeth 107 formed on the parallel frame portions 70, 70 integral with the tiltable support 9, as shown in Fig. 7. It will thus be evident that when the clutch 102 is connected the support 9 may be tilted about its 55 pivotal axis relative to the arm 8 in either direction, depending upon the direction of motor rotation. It will be evident, however, that if desired a suitable reverse mechanism may be provided to enable tilting of the support 9 in either direction relative to the arm without reversal of the motor.

The devices for swinging the support 10 horizontally about its axis 14 relative to the tiltable support 9, comprise a bevel gear 108 keyed to 60 and driven by the hinge shaft 69 and meshing, as shown most clearly in Fig. 9, with reverse bevels 109 and 110 journaled on a shaft 111, in turn suitably journaled within a housing 112 secured to the tiltable support 9. The reverse bevels 109, 110 are selectively connectible to the 65 shaft 111 by an operator-controllable jaw clutch 113 splined to the shaft. Keyed to the shaft 111 and driven thereby is a worm 114 meshing with a worm wheel 115 (see also Fig. 10) in turn keyed to a shaft 116 herein arranged parallel with the hinge shaft 69 and suitably journaled within the tiltable support 9. Keyed to the shaft 116 and driven thereby is a worm 117 meshing with the teeth of a worm gear segment 118 formed on the upper frame portion 73 of the 10 70 swingable support 10. It will thus be seen that when one or the other of the reverse bevels 109, 110 is connected to the shaft 111, the support 10 may be swung horizontally relative to the support 9 in either direction. It will also be noted that the worm gearings for swinging the arm, for tilting the support 9 and for swinging the support 10, are herein of the self-locking type and lock automatically the elements adjusted thereby when disconnected from their respective driving means. It will further be noted that the gearings for swinging the arm 8 and for tilting the support 9 relative to the arm may be so proportioned that when the arm is swung in one direction the support 9 is tilted in the 20 opposite direction at such speed as to maintain the head axis at all times in a substantially horizontal plane, and that the slow speed turntable rotation may be also so proportioned with the swinging speed of the support 10 that when the 25 cutter bar is in a vertical cutting position it may be swung horizontally about the support axis 14 while the kerf cutter at all times remains substantially parallel to a vertical plane.

Now referring to the mechanism for circulating 35 the cutter chain about the margin of the cutter bar, it will be observed that meshing with the bevel gear 95 is a bevel gear 120 (see Figs. 6 and 7) fixed to a longitudinal shaft 121, herein arranged with its axis at right angles to the hinge shaft 69 40 and lying in a longitudinal vertical plane including the axes of the shafts 64 and 93 and extending radially with respect to the turntable axis. The shaft 121 is suitably journaled within the tiltable support 9 and has fixed thereto and 45 drives a bevel gear 122 meshing with a bevel gear 123 journaled on the hinge shaft 72 and in turn meshing with a bevel gear 124 fixed to the rear end of a longitudinal shaft 125. The shaft 125 is journaled at its rear end within the swingable 50 support 10 and at its forward end within the frame 126 of the rotatable cutter head 11, and is arranged with its axis aligned with the head rotation axis and at right angles to the axis of the hinge shaft 72. Fixed to the forward end of the shaft 125 is a bevel gear 127 meshing with a large bevel gear 128 journaled on a shaft 129 herein arranged with its axis coincident with the axis of swinging movement of the cutter bar 15. The bevel gear 128 is connectible, by an operator- 55 controllable sliding clutch 130 of a usual design, to the shaft 129; and keyed to the outer end of this shaft and driven thereby is a chain sprocket 131 which engages and drives the cutter chain 16. The cutter bar 15 is attached to a cylindrical 60 supporting frame 132 secured, as by screws 133, to an annular bearing support 134 rotatably mounted in a bore 135 formed in the cutter head frame 126. A thrust ring 137 attached by screws 138 to the cutter head frame serves to retain the annular bearing support 134 within its bore.

The cutter head 11 is rotatably mounted on the 65 horizontally swingable support 10, and the mounting for the cutter head comprises an annular bearing support 140 secured, as by screws 141, to 70 75

- the circular frame portion 142 of the swingable support 10. Rotatably mounted on this bearing support is a bearing sleeve 143 secured by screws 144 to the cutter head frame 126 and having an inwardly directed flange 145 engaging the bearing support for retaining the sleeve in position thereon. The mechanism for rotating the cutter head about its axis relative to the support 10 and for swinging the cutter bar about its pivot, comprises a bevel gear 148 fixed to and driven by the bevel gear 128 and meshing with reverse bevels 149, 150 journaled on a shaft 151 extending transversely of the cutter head frame and at right angles to the shaft 129, and suitably journaled within the cutter head frame. The reverse bevels 149, 150 are selectively connectible to the shaft 151 by disc clutches 152, 153 having suitable operating means 154. Connectible to the shaft 151 by an operator-controllable sliding clutch 155 is a worm 156 meshing with a worm wheel 157 keyed to a longitudinal shaft 158, herein arranged parallel with the shaft 125 and suitably journaled within the cutter head frame. Keyed to the rear end of the shaft 158 is a spur gear 159 meshing with the teeth of an internal gear 160 formed on the annular bearing support 140. It will thus be seen that when the clutch 155 is connected and one or the other of the reverse bevel clutches 152, 153 is applied, the cutter head 11 may be rotated about the head axis in either of opposite directions to move the cutter bar completely about the head axis into different cutting positions. Connectible to the shaft 151 by a sliding clutch 161 is a worm 162 meshing with a worm gear 163 fixed to a shaft 164, herein arranged parallel with the shaft 129 and suitably journaled within the cutter head frame. Fixed to and driven by the shaft 164 is a spur gear 165 meshing with the teeth of an internal gear 166 formed on the annular bearing support 134 for the cutter bar. It will thus be seen that when the clutch 161 is connected and one or the other of the reverse bevel clutches 152, 153 is applied, the cutter bar may be swung about its pivot in either of opposite directions.
- The worm gearings for rotating the cutter head and swinging the cutter bar have self-locking teeth, and when disconnected from their drive lock automatically the parts in their adjusted position.
- It will be evident that the swivel support for the cutter bar on the cutter head and the mechanism for swinging the cutter bar 15 about its pivot relative to the cutter head 11 may be omitted and the cutter bar mounted in rigid relation with the cutter head frame. With this rigid cutter bar mounting, the cutter bar may be swung in its plane during the cutting operation about the vertical axis 14 by the mechanism for swinging the support 10 relative to the tiltable support 9. With this bar swinging mechanism omitted, the cutter bar may be swung in a vertical plane during the shearing operation by swinging the arm 9 to move the cutter bar about the arm axis 12 as a pivot and by independently swinging the tiltable support 9 relative to the arm 8.
- The mode of operation of the improved mining apparatus is as follows: The apparatus is propelled along the mine trackway at a relatively high transport speed through the planetary transmission 34 driven by the motor 25, it being understood that at that time the cutter bar is in the full-line position shown in Figs. 1 and 2. When the working face is reached, the high speed truck wheel drive is disconnected from the motor by releasing the friction band 36 and slid-
- ing the clutch member 38 into its neutral position. If it is desired to make a horizontal cut at or near the level of the mine floor in front of the end of the trackway in accordance with the arcw⁵wl method, the clutches controlling the swinging mechanisms for the arm and tiltable support 9 are applied, and upon running of the motor 63 in the proper direction, the parts are swung into the lower dotted-line position shown in Fig. 2, the support 9 swinging upwardly about its pivot 10 13 as the arm 8 is swung downwardly about its pivot 12, thereby to move the cutter bar 15 into the horizontal floor cutting position shown. The bar swinging mechanism is then operated and the cutter bar 15 is swung laterally from left 15 to right until its tip end is located adjacent the right-hand rib of the entry, the bar swinging controlling clutches thereafter being released. The operator then operates the sliding clutch 130, connecting the cutter chain 16 to its drive. With 20 the parts thus disposed, the planetary transmission mechanism 34 is operated, and upon connection of the clutch 42 the truck wheels are driven to propel the apparatus bodily along the mine trackway at a low cutting speed to effect 25 sumping of the cutter bar beneath the coal. After the completion of the sumping cut, the truck wheel drive is disconnected and the brake 59, 60 applied, holding the truck wheels against movement, and the bar swinging mechanism is then 30 operated to effect swinging movement of the cutter bar 15 about its pivot from its position adjacent the right-hand rib transversely across the coal face, to a position wherein its tip end is located adjacent the left-hand rib, the bar swing 35 controlling clutch thereafter being released. After the completion of the swinging cut, the motor 25 is reversed, and upon connection of the jaw clutch 42, the apparatus is propelled rearwardly along the mine trackway at a slow cutting speed to effect withdrawal of the cutter bar from beneath the coal face. The cutter bar and its adjustable supporting structure are then returned to the full-line position indicated in Figs. 1 and 2, and upon connection of the fast 40 speed drive of the planetary transmission, the apparatus is propelled bodily rearwardly along the trackway at a high transport speed to another working place.
- If it is desired to cut a horizontal kerf at or 50 near the level of the mine floor outside and below the level of the mine trackway in accordance with the arcw⁵wl method, the operator releases the turntable lock 53 and shifts the clutch member 38 of the planetary transmission into its high speed position, and then operates the clutch 42 to connect the gear 44 to the shaft 32, thereby causing the turntable 4, together with the cutting mechanism supported thereby, to be swung horizontally relative to the truck at a relatively high 55 cutter positioning speed from the central full-line position shown in Fig. 1 to a position wherein the cutter bar pivot lies outside of the trackway. During horizontal swinging movement of the turntable relative to the truck, the cutter bar may be swung simultaneously about its pivot in the opposite direction until the tip end of the cutter bar assumes a position adjacent the right-hand rib at a less angle with respect to the rib 60 than the angle of the pivoted arm structure. When the parts are thus disposed, with the bar pivot lying outside the trackway, the operator connects the swinging mechanisms for swinging the arm and support 9 to their drives, and the 65
- 70
- 75
- 75

arm is swung downwardly about its pivot while the support 9 is simultaneously swung upwardly until the parts assume the lower dotted-line position shown in Fig. 2, with the cutter bar at the 5 floor level outside the mine trackway. When the parts are thus disposed, the turntable is locked against rotation, and thereafter the truck wheels are driven from the motor 25 from the planetary transmission to propel the apparatus bodily along 10 the mine trackway at a low cutting speed to effect sumping of the cutter bar beneath the coal face. The brake 59, 60 is then set to hold the truck wheels stationary, the turntable lock released and the turntable rotation mechanism is 15 operated to effect rotation of the turntable at a relatively low speed to effect swinging of the adjustable supporting structure for the cutter bar laterally from right to left. Upon initial swinging movement of the arm structure, the cutter bar 15 is swung about its pivot in the opposite direction until the parts assume a straight-line position wherein the cutter bar lies in a vertical plane passing through the axes of the cutter bar pivot, the swingable support 10 and the 20 turntable. After the cutter bar has been straightened up, turntable rotation is continued, thereby swinging the cutter bar about the turntable axis from the right-hand rib until the tip end of the cutter bar lies adjacent the left-hand rib. After 25 the tip end of the cutter bar has reached the left-hand rib, the cutter bar is again swung about its pivot in a direction opposite from the direction of turntable rotation, while rotation of the turntable is continued; the turntable and cutter 30 bar swinging simultaneously in opposite directions at that time until they assume an angular position with the cutter bar disposed at a less angle with respect to the left-hand rib than the angle of the adjustable arm structure relative 35 thereto. The turntable rotation and bar swing mechanisms are then disconnected from their drives and the turntable lock connected, the brake released, and thereafter the apparatus is propelled bodily rearwardly along the mine track- 40 way at a low speed to effect withdrawal of the cutter bar from beneath the coal. After the completion of the bottom cut beneath the coal, the parts are again returned to their transport position, as indicated in full lines in Figs. 1 and 45 2, and the apparatus transported to another working place.

A horizontal kerf may be cut at or near the level of the mine roof by applying one or the other of the friction clutches 152, 153 of the 50 head rotating mechanism to effect rotation of the cutter head 11 about its axis from the full-line position shown in Fig. 2 to a position wherein the cutter bar overlies the bar support, the cutter bar moving through an arc of a circle 55 from its lower position to its upper position. When the parts are thus disposed, the clutches controlling the mechanisms for swinging the arm and tiltable support 9 about their respective pivots are operated to effect swinging movement 60 of the arm upwardly to the upper dotted-line position shown in Fig. 2, the support 9 swinging downwardly as the arm swings upwardly until the parts assume the top cutting position shown, with the cutter bar at the roof level. The cutter bar is then sumped in, swung transversely in 65 its plane and withdrawn from the coal face, in accordance with the usual arcwall method of cutting.

It will be noted that during any of the horizontal cutting operations above described, for 70

instance, when it is desired to cut a rolling or uneven floor or a pitching coal seam, the cutter bar may be tilted about transverse and longitudinal axes, i. e. about the axes of the cutter head and the tiltable support 9, to change its angle in altitude. For instance, if it is desired to tilt the tip 5 end of the cutter bar upwardly or downwardly, this may be accomplished simply by swinging the swingable support 9 upwardly and downwardly about its pivotal axis, while if it is desired to tilt the cutter bar edgewise, the cutter head is rotated about its axis. 10

A shear or vertical cut may be inserted in the coal face by applying one or the other of the reverse frictions 152, 153 of the head rotating 15 mechanism, thereby rotating the head 11 about its axis to bring the cutter bar into a position to swing vertically. During the shearing operation, the cutter bar is first sumped in, then swung downwardly in its plane and thereafter withdrawn from the coal face in a manner similar to that described above in connection with horizontal cutting in accordance with the usual arcwall method. It will further be noted that by rotating the turntable 4 and simultaneously swinging 20 the support 10 about its axis 14, the cutter bar may be positioned to cut vertical kerfs at any desired location between the center of the entry and either rib, one shearing position being indicated in dotted lines in Fig. 1. When the parts 25 are in the dotted-line position shown in Fig. 1, the arm 8 may be swung upwardly to position the cutter bar at the roof, and the apparatus may then be propelled bodily along the trackway to effect sumping of the cutter bar within 30 the coal face. After the completion of the sumping cut, the arm may be swung downwardly to move the cutter bar in the arcuate path about the arm pivot axis as a pivot to cut an upright, slightly curved kerf in the coal face from a point 35 adjacent the mine roof to a point at the mine floor. Thereafter, the cutter bar may be moved rearwardly to effect its withdrawal cut by propulsion of the apparatus bodily rearwardly along 40 the trackway. By swinging the cutter head support 10 about its vertical pivotal axis 14 from the dotted-line position shown in Fig. 1 to an angularly disposed position with the tip end of the cutter bar adjacent the left-hand rib, a similar 45 upright, slightly curved kerf may be cut 50 in the rib. By swinging the arm to the opposite side of the apparatus, a similar cut may be inserted in the opposite rib. It will further be noted that by rotating the head 11 the cutter 55 bar may be moved through an arc of a circle to shearing positions at either side of the cutter head axis, this being necessary when vertical kerfs are cut at opposite ribs.

As a result of this invention, it will be noted 60 that an improved coal mining apparatus is provided, having an improved adjustable supporting structure for the kerf cutter, whereby horizontal kerfs may be cut at or near the level of the mine floor, either in front of or outside and below the level of the mine trackway, horizontal 65 cuts at any desired location between the mine roof and mine floor, and vertical cuts at any desired location between the ribs of the entry. It will further be noted that by the provision of 70 the improved adjustable supporting structure, vertical kerfs may be cut in either rib of the entry, and that the apparatus may be operated to make shear or vertical cuts when the apparatus is supported and guided by a curved or un- 75

even trackway. It will further be noted that by the provision of the improved adjustable supporting structure for the kerf cutter, the latter may not only be positioned at any desired location between the mine roof and mine floor and the ribs of the entry, but also may be tilted about longitudinal and transverse axes to change its angle in altitude, thereby to accommodate itself to a rolling or uneven floor or pitching coal seam.

10 It will still further be evident that an improved coal mining apparatus is provided, wherein the adjusting mechanism for the kerf cutter is extremely flexible and has a wide range of adjustment, it being possible to operate the apparatus as a bottom cutter, top cutter, center cutter, shear cutter and slabbing machine, thereby enabling the apparatus to accommodate itself to practically every mining condition encountered. These and other uses and advantages will be apparent to those skilled in the art.

While I have in this application specifically described one form which my invention may assume in practice, it will be understood that this form is shown for illustrative purposes and that 25 the invention may be modified and embodied in various other forms without departing from its spirit or the scope of the appended claims.

What I claim as new and desire to secure by Letters Patent is:

30 1. In a mining apparatus, a portable base, a horizontal turntable on said base, an arm mounted on said turntable for movement relative thereto and at its outer extremity overhanging said base, a support mounted at the outer end of said arm to swing relative thereto about a vertical axis while said arm remains stationary, a cutter carrying head mounted on said swingable support for rotation relative thereto about a horizontal axis at right angles to the support axis, and a kerf cutter carried by said cutter head and positionable for cutting in different planes by rotation of said head upon its said horizontal axis of rotation.

45 2. In a mining apparatus, a portable base, a horizontal turntable on said base, an arm mounted on said turntable for movement relative thereto and at its outer extremity overhanging said base, a support mounted at the outer end of said arm to swing relative thereto about a vertical axis while said arm remains stationary, a cutter carrying head mounted on said swingable support for rotation relative thereto about a horizontal axis at right angles to the support axis, and a kerf cutter carried by said cutter head and adjustable with said head about the head axis into positions for cutting horizontal and vertical kerfs respectively.

60 3. In a mining apparatus, a portable base, a horizontal turntable on said base, an arm pivotally mounted on said turntable to swing in a vertical direction relative thereto and at its outer extremity overhanging said base, a support mounted at the outer overhanging extremity of said arm to swing relative thereto about a vertical axis, a cutter carrying head mounted on said swingable support for rotation relative thereto about a horizontal axis at right angles to the support axis, and a kerf cutter carried by said cutter head and positionable for cutting in different planes by rotation of said head upon its said horizontal axis of rotation.

70 4. In a mining apparatus, a portable base, a horizontal turntable on said base, an arm pivotally mounted on said turntable to swing in a ver-

tical direction relative thereto and at its outer extremity overhanging said base, a support mounted at the outer overhanging extremity of said arm to swing relative thereto about a vertical axis, a cutter carrying head mounted on 5 said swingable support for rotation relative thereto about a horizontal axis at right angles to the support axis, and a kerf cutter carried by said cutter head and adjustable with said head about the head axis into positions for cutting horizontal 10 and vertical kerfs respectively.

5. In a mining apparatus, a portable base, a horizontal turntable on said base, an arm pivotally mounted on said turntable to swing in a vertical direction relative thereto and at its outer extremity overhanging said base, a support mounted at the outer overhanging extremity of said arm to swing relative thereto about a vertical axis, a cutter carrying head mounted on 15 said swingable support for rotation relative thereto about a horizontal axis, a kerf cutter carried by said cutter head, and positionable for cutting in different planes by rotation of said head upon its said horizontal axis of rotation, and a motor mounted on said turntable and relative to which 20 said arm is swingable for swinging said arm.

6. In a mining apparatus, a portable base, a horizontal turntable on said base, an arm pivotally mounted on said turntable to swing in a vertical direction relative thereto and at its outer 30 extremity overhanging said base, a support mounted at the outer overhanging extremity of said arm to swing relative thereto about a vertical axis, a cutter carrying head mounted on 35 said swingable support for rotation relative thereto about a horizontal axis, a kerf cutter carried by said cutter head, and positionable for cutting in different planes by rotation of said head upon its said horizontal axis of rotation, and a motor mounted on said turntable and relative to which 40 said arm is swingable for swinging said arm and for swinging said support relative to said arm.

7. In a mining apparatus, a portable base, a horizontal turntable on said base, an arm pivotally mounted on said turntable to swing in a vertical direction relative thereto and at its outer extremity overhanging said base, a support mounted at the outer overhanging extremity of said arm to swing relative thereto about a vertical axis, a cutter carrying head mounted on 45 said swingable support for rotation relative thereto about a horizontal axis, a kerf cutter carried by said cutter head, and a motor mounted on said turntable and relative to which said arm is swing- 50 able for swinging said arm, for swinging said support relative to said arm, and for rotating said cutter head relative to said swingable support to change the plane of cutting.

8. In a mining apparatus, a portable base, a horizontal turntable on said base, an arm pivotally mounted on said turntable to swing in a vertical direction relative thereto, a tiltable support mounted at the outer end of said arm to swing relative thereto about an axis parallel with the 65 arm swing axis, a support mounted on said first support to swing horizontally relative thereto about a vertical axis, a cutter carrying head mounted on said last named support for rotation relative thereto about a horizontal axis, and a 70 kerf cutter carried by said cutter head.

9. In a mining apparatus, a portable base, a horizontal turntable on said base, an arm pivotally mounted on said turntable to swing in a vertical direction relative thereto, a tiltable sup- 75

port mounted at the outer end of said arm to swing relative thereto about an axis parallel with the arm swing axis, a support mounted on said first support to swing horizontally relative thereto about a vertical axis, a cutter carrying head mounted on said last named support for rotation relative thereto about a horizontal axis, and a kerf cutter carried by said cutter head and adjustable with said head about the head axis into 10 positions for cutting horizontal and vertical kerfs respectively.

10. In a mining apparatus, a portable base, a horizontal turntable on said base, an arm pivotally mounted on said turntable to swing in a vertical direction relative thereto, a tilttable support mounted at the outer end of said arm to swing relative thereto about an axis parallel with the arm swing axis, a support mounted on said first support to swing horizontally relative thereto about a vertical axis, a cutter carrying head mounted on said last named support for rotation relative thereto about a horizontal axis, a kerf cutter carried by said cutter head, and a motor 20 relative to which said arm is swingable for swinging said arm.

11. In a mining apparatus, a portable base, a horizontal turntable on said base, an arm pivotally mounted on said turntable to swing in a vertical direction relative thereto, a tilttable support mounted at the outer end of said arm to swing relative thereto about an axis parallel with the arm swing axis, a support mounted on said first support to swing horizontally relative thereto about a vertical axis, a cutter carrying head mounted on said last named support for rotation relative thereto about a horizontal axis, a kerf cutter carried by said cutter head, and a motor relative to which said arm is swingable for swinging said arm and for swinging said first support relative to said arm.

12. In a mining apparatus, a portable base, a horizontal turntable on said base, an arm pivotally mounted on said turntable to swing in a vertical direction relative thereto, a tilttable support mounted at the outer end of said arm to swing relative thereto about an axis parallel with the arm swing axis, a support mounted on said first support to swing horizontally relative thereto about a vertical axis, a cutter carrying head mounted on said last named support for rotation relative thereto about a horizontal axis, a kerf cutter carried by said cutter head, and a motor relative to which said arm is swingable for swinging said arm, for swinging said first support relative to said arm and for swinging said second support relative to said first support.

13. In a mining apparatus, a portable base, a horizontal turntable on said base, an arm pivotally mounted on said turntable to swing in a vertical direction relative thereto, a tilttable support mounted at the outer end of said arm to swing relative thereto about an axis parallel with the arm swing axis, a support mounted on said first support to swing horizontally relative thereto about a vertical axis, a cutter carrying head mounted on said last named support for rotation relative thereto about a horizontal axis, a kerf cutter carried by said cutter head, and a motor relative to which said arm is swingable for swinging said arm, for swinging said first support relative to said arm and for swinging said second support relative to said first support, and for rotating said cutter head relative to said second support.

14. In a mining apparatus, a portable base, an arm pivotally mounted on said base to swing vertically relative thereto, a tilttable support pivotally mounted on the outer end of said arm to swing relative thereto about an axis parallel with the arm swing axis, a second support swingably mounted on said tilttable support to swing relative thereto about a vertical axis, and a cutter head mounted on said last named support for rotation relative thereto about a horizontal axis.

15. In a mining apparatus, a portable base, an arm pivotally mounted on said base to swing vertically relative thereto, a tilttable support pivotally mounted on the outer end of said arm to swing relative thereto about an axis parallel with the arm swing axis, a second support swingably mounted on said tilttable support to swing relative thereto about a vertical axis, and a cutter head mounted on said last named support for rotation relative thereto about a horizontal axis arranged at right angles to the arm swing axis and the axis of swing of said first support.

16. In a mining apparatus, a portable base, an arm pivotally mounted on said base to swing vertically relative thereto about a horizontal axis extending transversely of said base, a tilttable support pivotally mounted on the outer end of said arm to swing relative thereto about an axis parallel with the arm swing axis, a second support swingably mounted on said tilttable support to swing relative thereto about a vertical axis, and a cutter head mounted on said last named support for rotation relative thereto about a horizontal axis.

17. In a mining apparatus, a portable base, a frame mounted on said base to swing horizontally relative thereto, an arm pivotally mounted on said frame to swing vertically relative thereto, a tilttable support pivotally mounted at the outer end of said arm, a second support pivotally mounted on said tilttable support to swing relative thereto about a vertical axis, a vertical-kerf cutter mounted on said last named support, and means for adjusting said kerf cutter, while said vertical axis remains vertical, relative to said tilttable support selectively into mutually parallel, vertical-kerf cutting positions at opposite sides of a vertical plane including the vertical axis of said second support.

18. In a mining apparatus, a portable base, a frame mounted on said base to swing horizontally relative thereto, an arm pivotally mounted on said frame to swing vertically relative thereto, a tilttable support pivotally mounted at the outer end of said arm, a second support pivotally mounted on said tilttable support to swing relative thereto about a vertical axis, a vertical-kerf cutter mounted on said last named support, means for adjusting said kerf cutter relative to said tilttable support, while said vertical axis remains vertical, selectively into mutually parallel, vertical-kerf cutting positions at opposite sides of a vertical plane including the vertical axis of said second support, said arm being swingable to move the kerf cutter in an upright slightly curved path about the arm swing axis as a pivot in substantially any vertical-kerf cutting position of said bar.

19. In a mining apparatus, a portable base, a frame mounted on said base to swing horizontally relative thereto, an arm pivotally mounted on said frame to swing vertically relative thereto, a tilttable support pivotally mounted at the outer end of said arm, a second support pivotally mounted

- on said tiltable support to swing relative thereto about a vertical axis, a vertical-kerf cutter mounted on said last named support, means for adjusting said kerf cutter relative to said tiltable support, while said vertical axis remains vertical, selectively into mutually parallel, vertical-kerf cutting positions at opposite sides of a vertical plane including the vertical axis of said second support, said arm being swingable in one direction relative to said base and said last named support swingable in the opposite direction relative to said arm to move the kerf cutter into different parallel vertical kerf cutting positions in either adjusted position of said kerf cutter.
- 15 20. In a mining apparatus, a portable base, a frame mounted on said base to swing horizontally relative thereto, an arm pivotally mounted on said base to swing vertically relative thereto, a tiltable support pivotally mounted on the outer end of said arm to swing relative thereto about an axis parallel with the arm swing axis, a second support pivotally mounted on said tiltable support to swing relative thereto about a vertical axis, a cutter head mounted on said last named support 25 for rotation relative thereto about a horizontal axis, and a kerf cutter carried by said cutter head.
21. In a mining apparatus, a portable base, a support mounted on said base to turn about a vertical axis, an arm pivotally mounted on said support to swing in a vertical direction relative thereto, a frame mounted on said arm for tilting adjustment with respect thereto about rectangularly related axes, a cutter head rotatably mounted on said tiltable frame, and a kerf cutter carried 30 by said cutter head and rotatable therewith with respect to said tiltable frame into positions for cutting horizontal and vertical kerfs respectively.
- 35 22. In a mining apparatus, a portable base, a support mounted on said base for swinging adjustment in a vertical direction with respect thereto about a horizontal axis, a frame carried by said swinging support for tilting adjustment with respect thereto about rectangularly related axes, a cutter head rotatably mounted on said tiltable frame, and a kerf cutter carried by said cutter 40 head and rotatable therewith about the head axis into positions for cutting horizontal and vertical kerfs respectively.
- 45 23. In a mining apparatus, a portable base, an arm structure pivotally mounted on said base to swing in a vertical direction with respect thereto, a frame carried by said arm structure for tilting adjustment with respect thereto about rectangularly related axes, a cutter head rotatably mounted on said tiltable frame, and a kerf cutter carried by said cutter head and rotatable therewith about the head axis into positions for cutting horizontal and vertical kerfs respectively.
- 50 24. In a mining apparatus, a portable base, an arm pivotally mounted on said base to swing in a vertical direction with respect thereto, a support pivotally mounted on the outer extremity of said arm to swing relative thereto about an axis parallel with the arm pivot axis, a second support pivotally mounted on said first support to swing relative thereto about an axis at right angles with respect to the pivotal axis of said first support, a third support mounted on said second support to rotate relative thereto about an axis at right angles to the axes of said first and second supports, and a kerf cutter carried by said third support and positionable by rotation of said 55 third support on its respective axis of rotation for cutting in different planes.
- 55 25. In a mining apparatus, a portable base, an arm pivotally mounted on said base to swing relative thereto, a support pivotally mounted on said arm to swing relative thereto about an axis parallel with the arm pivot axis, a second support pivotally mounted on said first support to swing relative thereto about an axis at right angles with respect to the pivotal axis of said first support, a third support mounted on said second support to rotate relative thereto about an axis at right angles to the axes of swing of said first and second supports, a fourth support pivotally mounted on said third support to 60
- 60 65 70 75 76

- tion of said third support on its respective axis of rotation for cutting in different planes, and a motor relative to which said supports are adjustable for actuating said kerf cutter, for effecting tilting movement of said supports with respect to said arm and for swinging said arm about its pivot.
38. In a mining apparatus, a portable base, an arm pivotally mounted on said base to swing relative thereto, a support pivotally mounted on said arm to swing relative thereto about an axis parallel with the arm pivot axis, a second support pivotally mounted on said first support to swing relative thereto about an axis at right angles 15 with respect to the pivotal axis of said first support, a third support mounted on said second support to rotate relative thereto about an axis at right angles to the axes of swing of said first and second supports, a fourth support pivotally 20 mounted on said third support to rotate relative thereto about an axis at right angles to the axis of rotation of said third support, a kerf cutter carried by said fourth support, and a motor relative to which said supports are adjustable for 25 actuating said kerf cutter, for effecting tilting movement of said supports with respect to said arm and for swinging said arm about its pivot.
39. In a mining apparatus, a portable base, an arm pivotally mounted on said base to swing relative thereto, a support pivotally mounted on said arm to swing relative thereto about an axis parallel with the arm pivot axis, a second support pivotally mounted on said first support to swing relative thereto about an axis at right 35 angles with respect to the pivotal axis of said first support, a third support mounted on said second support to rotate relative thereto about an axis at right angles to the axes of swing of said first and second supports, a fourth support pivotally 40 mounted on said third support to rotate relative thereto about an axis at right angles to the axis of rotation of said third support and lying in a plane parallel to a plane including the axis of said second support, a kerf cutter carried 45 by said fourth support, and a motor relative to which said supports are adjustable for actuating said kerf cutter, for effecting tilting movement of said supports with respect to said arm and for swinging said arm about its pivot.
40. In a mining apparatus, a portable base, a horizontal turntable on said base, an arm swingably mounted on said turntable for movement relative thereto and at its outer extremity overhanging said base, a support mounted at the 55 outer extremity of said arm to swing relative thereto about a vertical axis, a cutter carrying head mounted on said swingable support for rotation relative thereto about a horizontal axis at right angles to the support pivot axis, a kerf 60 cutter carried by said cutter head and positionable for cutting in different planes by rotation of said head upon its said horizontal axis of rotation, and independently operable motor operated devices for rotating said turntable to swing 65 said arm horizontally and for swinging said support relative to said arm while the latter remains stationary as regards swinging movement about its pivotal axis to vary the angular position of the head axis.
41. In a mining apparatus, a portable base, a horizontal turntable on said base, an arm pivotally mounted on said turntable for movement relative thereto and at its outer extremity overhanging said base, a support mounted at the outer 70 end of said arm to swing horizontally into dif- 75
- ferent angularly related positions with respect thereto about a vertical axis while said arm remains stationary as regards swinging movement about its pivotal axis, a cutter carrying head mounted on said swingable support for rotation relative thereto about a horizontal axis at right angles to the support pivot axis, and a kerf cutter carried by said cutter head and positionable for cutting in different planes by rotation of said head upon its said horizontal axis of rotation.
42. In a mining apparatus, a portable base, an arm pivotally mounted on said base to swing in a vertical direction relative thereto, a cutter carrying head rotatable on a horizontal axis and carrying a kerf cutter which is positionable for cutting in different planes by rotation of said head upon its said horizontal axis of rotation, and a universal pivotal supporting structure intervening said arm and said head for supporting the latter, said head being swingable through said universal pivotal supporting structure in horizontal and vertical directions relative to said arm.
43. In a mining apparatus, a portable base, an arm pivotally mounted on said base to swing in horizontal and vertical directions relative thereto, a cutter carrying head rotatable on a horizontal axis and carrying a kerf cutter which is positionable for cutting in different planes by rotation of said head upon its said horizontal axis of rotation, and a universal pivotal supporting structure intervening said arm and said head for supporting the latter, said head being swingable through said universal pivotal supporting structure in horizontal and vertical directions relative to said arm.
44. In a mining apparatus, a portable base, an arm pivotally mounted on said base to swing in a vertical direction relative thereto, a cutter carrying head rotatable on a horizontal axis and carrying a kerf cutter which is positionable for cutting in different planes by rotation of said head upon its said horizontal axis of rotation, and a pivotal supporting structure intervening said arm and said head for supporting the latter including relatively swingable supporting elements arranged on rectangularly related axes, said cutter head being swingable through said pivotal supporting structure in horizontal and vertical directions relative to said arm.
45. In a mining apparatus, a horizontal turntable, an arm pivotally mounted on said turntable to swing in a vertical direction relative thereto, a support pivotally mounted on the outer extremity of said arm to swing in a vertical direction relative thereto about a horizontal axis, a second support pivotally mounted on said first support to swing in a horizontal direction relative thereto about a vertical axis, and a kerf cutter pivotally mounted on said second support to swing relative thereto in horizontal planes about an axis lying in a vertical plane parallel to a vertical plane including the pivotal axis of said first support.
46. In a mining apparatus, a horizontal turntable, an arm pivotally mounted on said turntable to swing in a vertical direction relative thereto, a support pivotally mounted on the outer extremity of said arm to swing in a vertical direction relative thereto about a horizontal axis, a second support pivotally mounted on said first support to swing in a horizontal direction relative thereto about a vertical axis, a cutter carrying head rotatably mounted on said second support to turn on a horizontal axis arranged at

right angles to the pivotal axis of said second support, and a kerf cutter carried by said cutter head and adjustable into different angularly related cutting planes by rotation of said cutter carrying head upon said horizontal axis.

47. In a mining apparatus, a horizontal turntable, an arm pivotally mounted on said turntable to swing in a vertical direction relative thereto, a support pivotally mounted on the outer extremity of said arm to swing in a vertical direction relative thereto about a horizontal axis, a second support pivotally mounted on said first support to swing in a horizontal direction relative thereto about a vertical axis, a cutter carrying head rotatably mounted on said second support to turn on a horizontal axis arranged at right angles to the pivotal axis of said second support, and a kerf cutter pivotally mounted on said cutter head to swing with respect thereto about an axis arranged at right angles with respect to said head axis.

48. In a mining apparatus, a portable base, a horizontal turntable on said base, an arm mounted on said turntable for movement relative thereto and at its outer extremity overhanging said base, a support mounted at the outer end of said arm to swing relative thereto about a vertical axis, a cutter carrying head mounted on said swing-

able support for rotation relative thereto about a horizontal axis at right angles to the support axis, said support being swingable horizontally about said vertical axis to move the cutter head axis into different angularly related positions 5 with respect to said arm and turntable, and a kerf cutter carried by said cutter head and adjustable into different angularly related cutting planes by rotation of said cutter carrying head upon said horizontal axis. 10

49. In a mining apparatus, a portable base, a horizontal turntable on said base, an arm mounted on said turntable for movement relative thereto and at its outer extremity overhanging said base, a support mounted at the outer end of said arm to swing relative thereto about a vertical axis, a cutter carrying head mounted on said swingable support for rotation relative thereto about a horizontal axis at right angles to the support axis, said support being swingable horizontally about said vertical axis to move the cutter head axis into different angularly related positions 15 with respect to said arm and turntable, and a kerf cutter carried by said cutter head and adjustable with said head about the head axis into positions 20 for cutting horizontal and vertical kerfs respectively. 25

CHARLES F. OSGOOD.
